UNITED STATES PATENT OFFICE

2,469,432

SUPERSPEED ELEVATED RAILWAY

Walter Cecil Cox, Englewood, Colo.

Application July 24, 1944, Serial No. 546,340

2 Claims. (Cl. 104—135)

1

This invention relates to an elevated super-speed railway and has for its principal object the provision of a vehicle and track design which will allow exceedingly high speeds to be efficiently and safely obtained without damage to wheel bearings or traction surfaces.

Other objects of the invention are to provide an over-head railway which will be economical to construct and which will be exceedingly rigid and strong; to provide driving means which will obtain maximum traction on the track with a minimum of wear, and to provide a construction in which the surface of a belt may be employed to obtain traction on track so as to eliminate the inefficient wheel contact usually employed for driving purposes.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 is a perspective view of one form of the improved super-speed, elevated railway;

Fig. 2 is an enlarged, fragmentary, sectional view of the driving portion of a car as used on the railway of Fig. 1;

Fig. 3 is a cross section therethrough, taken on the line 3—3, Fig. 2; and

Fig. 4 is a fragmentary horizontal section, looking downwardly, on the upper drive wheel.

The improved elevated railway is designed to be supported upon spaced-apart pairs of vertical posts 10, each terminating at its top in a head bracket member 11. The posts of each pair are joined together by means of cross braces 12. The head bracket members 11 support arch members 13 which join the tops of each pair of posts. The posts are of varying length depending upon the variations in elevation of the supporting terrain, it being intended that the track shall maintain a uniform grade alignment regardless of the surface profile.

The track comprises two parallel longitudinal truss beams 14 supported on the posts 10. The beams 14 carry, along their upper edges, a continuous series of spaced-apart rollers 15. The axles of the rollers 15 are mounted between two parallel roller plates 16 supported along the tops of the beams 14. These rollers are preferably

2

provided with suitable antifriction bearings and are of relatively small diameter so that very little power will be required to overcome their static inertia.

5 The arch members 13 support an upper traction track 17, preferably formed of an inverted channel-shaped member provided with an internal friction pad 18 of rubber or similar material. The cross braces 12 support a lower traction track 19.

The track structure is designed to receive a tubular streamlined car 20, such as illustrated in Fig. 1, having forward and rear passenger compartments 21 separated by a power compartment 22. The car is supported by longitudinally extending runners 23 secured along each side of the midportion thereof over the track rollers 15. The runners are sufficiently long to simultaneously engage a plurality of the rollers so that, as the car moves, they will always be supported by a number of the rollers and as the runners pass from one roller they will have entered upon another preceding roller. The car itself carries no supporting wheels.

20 25 The car may be driven along the roller tracks in any desired manner. The preferred method of driving the car is illustrated in detail in Fig. 2. It comprises one or more motors or power units 24. One of the units 24 is connected, by means 30 of a relatively heavy traction belt 25, to a lower drive wheel 26. The wheel 26 is mounted on a crank bearing 27 in a transversely extending axle 28 which extends across the car and into the runners 23 to provide a support for the latter.

35 30 The drive wheel 26 is mounted immediately above the lower traction track 19 so that the belt 25 will rest on the track. Thus the tractive effort is between the belt 25 and the track. The wheel 26 does not contact the track. It will be noted that the rotative effect of the belt 25, in combination with the reaction of the crank 27, draws the wheel downwardly to squeeze the belt snugly against the track. The outer surface of the belt, if desired, may be concave, as indicated 40 at 29, to conform to the shape of the track 19.

45 Another of the power units 24 actuates an upper belt 30 which is trained round an upper drive wheel 31 positioned immediately below the upper channel track 17. The upper drive wheel is also 50 mounted on a crank bearing 47 in a cross axle 32 extending across the car into the runners 23 at the sides thereof. The crank bearing 47 is constantly urged, by means of springs 33, to force the outer surface of the belt 30 against the friction pad 18 of the upper track. This contact is

also assisted by the pull of the upper reach of the belt 34 during operation.

The belts 25 and 30 may be of any type found most suitable for the purpose. It will be noted that the entire tractive effort is transmitted to the tracks by means of the endless belts 25 and 30. These belts contact the track at only a portion of their lengths at any one time so that the remainder of the belt has ample time for cooling and the wear is distributed over the entire length thereof. The entire pull upon the belt is transmitted directly to the track without intermediate elements.

The car is preferably provided with a forward guide wheel 34 which rides in the channel of the upper track to maintain the car in longitudinal alignment therewith.

An exceedingly high speed may be attained by the improved car since there are no track engaging or supporting wheels on the cars. This eliminates all possible over-heating of wheels and bearing boxes. The supporting rollers only operate individually for an instant so that they do not become over-heated or worn. The cars are perfectly streamlined so as to reduce air resistance to a minimum and all sharp grades and curves are eliminated by the over-head structure. Therefore, high speed operation is economical and entirely safe and practical.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. An elevated railway comprising: a plurality of aligned pairs of supporting posts; a pair of spaced-apart, horizontal beams supported in parallel relation by said posts; a continuous series of spaced-apart rollers extending above and aligned along each beam with their axes at right angles to the axis of said beams; a tubular, stream-lined car positioned between said beams; a horizontally extending runner member projecting from each side of said car, each runner member resting upon one of a series of rollers, said runner members being sufficiently long to

cover a plurality of said rollers and being positioned in a horizontal plane substantially bisecting the vertical height of said car so that substantially one-half the car will be suspended below the plane of said rollers; a traction rail extending parallel to said beams below said car; and driving means engaging said rail to propel said car therealong.

2. An elevated railway comprising: a plurality of aligned pairs of supporting posts; a pair of spaced-apart, horizontal beams supported in parallel relation by said posts; a continuous series of spaced-apart rollers extending above and aligned along each beam with their axes at right angles to the axis of said beams; a tubular, stream-lined car positioned between said beams; a horizontally extending runner member projecting from each side of said car, each runner member resting upon one of a series of rollers, said runner members being sufficiently long to cover a plurality of said rollers and being positioned in a horizontal plane substantially bisecting the vertical height of said car so that substantially one-half the car will be suspended below the plane of said rollers; a traction rail extending parallel to said beams above said car; and traction drive means engaging said rail to propel said car therealong.
